UNITED STATES PATENT OFFICE.

GARRETT F. SPEER, OF PHILADELPHIA, PENNSYLVANIA.

DRYING-KILN.

SPECIFICATION forming part of Letters Patent No. 252,272, dated January 10, 1882.

Application filed November 5, 1881. (No model.)

To all whom it may concern:

Be it known that I, GARRETT F. SPEER, of Philadelphia, in the county of Philadelphia and State of Pennsylvania, have invented certain new and useful Improvements in Drying-Kilns; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a vertical central section of my improved kiln or drier. Fig. 2 is a plan or top view of the same with the roof removed. Fig. 3 is detail of the nozzle and gutter.

The same part is indicated by the same letter wherever it occurs in the drawings.

The object of my invention is to provide an economical and efficient apparatus applicable to all the purposes to which driers are commonly applied, from the drying of lumber in large kilns to the drying of fruits in smaller chambers.

25 The principle of my invention consists in using the same cold air which produces the circulation in the drying-chamber to cool the condensing-surfaces which extract the moisture and give direction to the air-currents, and in 30 the saving of heat by the indefinitely repeated heating, circulation, and drying of the same air and its confinement in the kiln until a predetermined limit of pressure has been reached and a relieving-valve opened.

35 My invention consists in confining the matters to be dried in a close chamber heated by air passing around and between steam-pipes, and forcing into said chamber, by means of a condensing-fan or air-pump, atmospheric air 40 through a broad flat metallic tuyere or nozzle, whose surface forms a condenser upon which the injected air, after being heated by passing between steam-pipes and circulating among the matters to-be dried and depriving them of 45 their moisture, impinges and parts with the water it has absorbed, and is again heated, circulated, and dried, the operation being continuous, the fan keeping up a constant and regulated pressure within the kiln, the condensed air only escaping through the safety-valve when the fixed limit of pressure has been

reached, all as hereinafter more specifically set forth.

In the accompanying drawings, which represent a lumber-drying kiln with my improvement, S marks the walls or sides of the kiln; R, the roof; C, the chimney; and V, the relief or safety valve, loaded to any desired limit of pressure.

K is the drying-chamber, having sliding doors D at either end for the entrance and exit of cars bearing lumber. The floor of this chamber is composed of the longitudinal steam-pipes P, communicating at the ends with the "manifolds" M M'. The steam enters through 65 inlet-pipe I, manifold M, and exhausts through manifold M' into a suitable steam-trap. (Not shown.)

F is a condensing-fan, driven by any suitable power, and communicating with a chamber, 70 A, below the floor of chamber K, by means of a nozzle, N, which is flattened and broadened as it approaches and enters the kiln in the manner represented in Fig. 2, the area of the nozzle being the same at the delivery end as at its 75 junction with the fan. The part of the nozzle within the kiln is equal in width to the width of the kiln, and has a downward inclination, as shown in Fig. 1. Its lower margin forms a 80 gutter connecting by trapped pipe O with a well or tank, W. The delivery-opening of the nozzle is below the gutter G, as shown in Figs. 1 and 3.

The operation is as follows: The lumber being introduced into chamber K and the steam 85 let into the pipes P, the fan F is set in operation, and sends a uniform current of air into the chamber A. This current fills all parts of the chamber and passes up between the pipes P, by which it is heated, into chamber K, where 90 it soon becomes loaded with the moisture it draws from the green lumber. A portion of the air thus laden with moisture comes into contact with the upper surface of the flattened metallic nozzle N, which is kept at a low temperature by the cold air constantly flowing through it. The air thus dried and partially cooled descends into chamber A, and is again driven along with the entering current, again heated, loaded with moisture, and relieved of it by condensation as before, the operation being indefinitely repeated, and the water of condensation 95 100

running off by gutter G and trapped pipe O in-
to the well or tank W. The constant action
of the fan keeps up a pressure in the kiln, which
is relieved, whenever it reaches a prescribed
5 limit, by the automatic action of the loaded
valve V. It is only when the valve acts that
any portion of the heat supplied by the steam
escapes and is lost. The economy of heat
in this direction is therefore obvious. It is still
10 further enhanced by the fact that, owing to the
ceaseless flow of the air into the revolving cur-
rents indicated by the arrows, the work can be
done at a much lower temperature than in kilns
of the ordinary construction. I use a tempera-
15 ture of from 130° to 140° Fahrenheit, as against
a temperature of from 175° to 250° , used in
common kilns. Besides the saving of fuel in-
cident to this, there is a great advantage aris-
20 ing from the gradual character of the heating,
which prevents the surface of the wood from
becoming baked and sealed, while much of its
moisture remains within to expand and "check"
the wood by its escape through the dried and
25 clogged surface.

It should be observed that when from any

cause it becomes desirable to increase the con-
densing power of the flattened nozzle the air
for the supply of the fan may be drawn from
a refrigerating-chamber of any suitable con-
struction.

30

I am aware that close kilns have been used
and water-cooled condensers have been em-
ployed in them. Such a combination I do not
claim; but

What I do claim, and desire to secure by 35
Letters Patent, is—

The combination, in a drying apparatus, of
a close chamber controlled by a relief-valve,
steam-heating pipes, a condensing-fan or air-
pump, and an air-cooled condenser formed by 40
the flattened nozzle or tuyere of the fan, all
constructed and arranged for conjoint opera-
tion, substantially in the manner described.

In testimony that I claim the foregoing as
my own invention I affix my signature in pres- 45
ence of two witnesses.

GARRETT F. SPEER.
